(57) **CLAIM**

We claim the ornamental design for a bayonet stun gun, as shown and described.

DESCRIPTION

FIG. 1 is a perspective view of a bayonet stun gun showing our new design with the broken line showing of a weapon for illustrative purposes only forming no part of the claimed design.

FIG. 2 is a front elevational view of the bayonet stun gun of FIG. 1;

FIG. 3 is a bottom elevational view of FIG. 2;

FIG. 4 is a side elevational view of FIG. 2;

FIG. 5 is a top elevational view of FIG. 2; and, FIG. 6 is a rear elevational view of FIG. 2.
